John F. LaSoy

UNITED STATES PATENT OFFICE.

JOHN P. TARBOX, OF BUFFALO, NEW YORK, ASSIGNOR TO CURTISS AEROPLANE & MOTOR CORPORATION, A CORPORATION OF NEW YORK.

SPOKE-STAY.

1,223,298.

Specification of Letters Patent. Patented Apr. 17, 1917.

Application filed November 27, 1915. Serial No. 63,743.

To all whom it may concern:

Be it known that I, JOHN P. TARBOX, a citizen of the United States, residing at Buffalo, in the county of Erie and State of

5 New York, have invented certain new and useful Improvements in Spoke-Stays, of which the following is a specification.

This invention relates to wire stays of the character employed for adjustable trussing 10 in aeroplane frame-works, and in particular relates to a novel stay partaking of a spoke construction, somewhat after the manner of those spokes employed in the wire wheels of motorcycles, automobiles and similar vehicles.

Customary practice in regard to the use of truss stays as braces for the fuselage, planes, etc., of an aeroplane involves the use of clevises at the extremities of each wire for 20 the anchorage thereof, and it is necessary to splice or wrap a loop in each wire terminus to form an eyelet for connection to its clevis. This method produces a stay whose strength is weakened by its splices or loop and which necessitates much care and labor in attachment.

It is, accordingly, the object of the present invention to provide a wire spoke bracing, which shall be formed of the same material 30 and to substantially the same dimensions, save for integral end enlargements, as made use of for the old wiring, but having a means of anchorage which obviates all necessity for splicing or looping the wire ends or employing clevises of any description.

More specifically, the object of the present invention is to provide truss spoke bracing comprising two portions with enlarged extremities, one extremity of each being headed 40 for a spoke anchorage and the other enlarged extremities of the portions being adjustably connected by a tensioning member, and this object is accomplished by such means as are illustrated in the accompanying drawing, described in the following 45 specifications and then more particularly pointed out in the claims which are appended hereto and form a part of this application.

With reference to the drawings, in which 50 there is illustrated one embodiment of the invention, and throughout the several views, of which like characters of reference designate similar parts,

Figure 1 is a fragmentary perspective 55 view showing the connection of a pair of fuselage struts to a longeron, illustrating the method of anchoring the truss stay of this invention to the fuselage clip;

Fig. 2 is a face view of the clip employed 60 as an anchoring plate;

Fig. 3 is a vertical sectional view through the clip plate illustrating a spoke shank in the act of being anchored therein; and

Fig. 4 is a similar view after the spoke 65 shank has been finally positioned.

Each single length of the wire bracing adapted to connect the points to be stayed consists of two portions, since it is necessary to interpose a turnbuckle or a similar means 70 controlling adjustment of the tension on the wire when equalizing the stresses on the braced portion of the fuselage, or other part to be stayed. These separate parts may be termed the spoke wire, which is designated 75 5 and the spoke shank, denoted by the numeral 6. Each has a desirable spoke anchorage, an example of which is afforded by the fuselage clip 7 of Fig. 1, which embraces the longeron 8 on two of its faces and 80 is bent as denoted by the numeral 9 to provide offset surfaces 10 which contact directly with vertical and horizontal fuselage struts 11 and 12. It will be understood that this 85 type of anchorage for the spoke stay of this invention is merely typical of a certain class of uses for which the stay is fitted, and is not a limitation on the universal applicability of the stay. The offset surfaces 10 of the particular clip here shown are usually connected by an arcuate bolt 13 of a flattened U-shape which passes through intersecting struts 11 and 12 and is secured by the customary nuts 14 acting against the surfaces 10. 90 95

Both the spoke wire 5 and the spoke shank 6 are formed with an enlarged extremity 15 which terminates in a still further enlarged

and flattened head, or anchoring button 16. The body portion of the wire 5 is of the same dimension and material as that of the ordinary wire bracing, but at the end opposite 5 to the enlarged portion 15 it is formed with a second enlarged extremity 17 which is adapted to enter one end of the female turnbuckle 18 or a similar adjusting member, the extremity 17 being provided with exterior screw threads 19 adapted to mate with similar threads provided in the turnbuckle. The spoke shank 6 is not drawn out or reduced to provide a wire body portion, in the single embodiment illustrated, although it 10 is contemplated by this invention to form the member 6 similarly to the member 5 if it is found desirable to do so. At the present time, however, adjusting members, such as the turnbuckle 18, with which the wires 15 are equipped are preferably stationed adjacent one of the anchorage points of the wire, as a pair of these wires frequently intersect or pass each other and it would not be desirable to have the turnbuckles of such 20 wires centrally positioned thereon for an inevitable contact which might work an injury to the trussing structure. For this reason the spoke shank 6 has its portion 15, upon which is carried the head 16 formed 25 on one end with the threads 19 for engagement directly to the turnbuckle.

Figs. 3 and 4 illustrate steps in the method of anchoring a spoke extremity. It will be understood that while the illustrations are 30 concerned with the spoke shank 6, as is also the immediately following description, the manner of anchoring the spoke stay proper is precisely similar. The turnbuckle extremity of the shank, or stay is threaded 35 through the round-edged anchoring aperture 20 which is provided in the securing ears 21 of the clip or other element to which the stay of this invention is to be attached. The shank 15 is then bent through an angle 40 of 90° with respect to the axis of its head 16, as shown in Fig. 3, the other portion of the stay having been treated in the same manner at its attaching point, the two inner, threaded ends are joined by a turnbuckle 45 which is rotated to secure the desired tension on the stay as a whole, which will draw the latter into the position of actual service shown in Fig. 4. In any alignment, however, the round-edged aperture will afford 50 the bent extremity of shank or stay the play necessary for take-up oscillations.

The U-bolt 13 also serves as an anchorage point for the stays adapted to extend transversely of the fuselage to connect diagonal 55 longerons 8, but although a spoke anchorage is not possible here the use of a clevis is also dispensed with by forming the enlarged shank 15 with a loop 22 in place of the spoke

head 16. Owing to the increased diameter of the shank at each extremity of the stay, 60 it is possible to provide such loops without weakening the structure to an extent resultant in the old method.

From the foregoing it is believed that the advantages dependent upon the employment 70 of the novel spoke stay of this invention should be apparent without recapitulation. It is desired to emphasize the fact, however, that later adaptations may be made in accordance with conditions concurrent to their 75 adoption that shall be entertained as within the scope of the invention as it is defined by the appended claims.

What is claimed is:

1. A spoke stay including separable portions, each of said portions being formed with an enlarged extremity and a head extending laterally therefrom. 80

2. A spoke stay including separable portions, each portion having one enlarged extremity angularly headed for anchorage and means adjustably connecting the portions to determine the tension of said stay. 85

3. A spoke stay including a wire portion and a shank portion formed with enlarged 90 extremities, said enlarged extremities being provided with bent anchorage heads.

4. A spoke stay including a wire portion and a shank portion, each portion having an enlarged angularly extending headed extremity for separate anchorage and an enlarged exteriorly threaded extremity for 95 mutual connection.

5. A spoke stay including a wire portion having enlarged extremities respectively angularly headed and threaded, a shank portion having its extremities similarly headed and threaded and a turnbuckle connecting the threaded extremities of said portions. 100

6. A spoke stay including a wire portion 105 having enlarged extremities, one of which is provided with an angularly extended head, a shank portion also formed with an angularly extended head and means connecting the other extremities of said portions. 110

7. As truss bracing in an aeroplane framework, the combination with apertured anchor plates of spoke stays to connect such plates, each stay including a wire portion, 115 a shank portion and means relating such portions, said shank portion being anchored in one of said plates and said wire portion having a spoke-headed anchorage in another of said plates. 120

8. As truss bracing in an aeroplane framework, the combination with anchor plates formed with round-edged apertures, of a spoke stay including a wire portion, a shank portion, means relating said portions, and a 125 spoke head formed on each portion for an-

chorage in said apertured plates, said spoke heads being bent at an angle to respective portions.

9. As truss bracing in an aeroplane frame-
5 work, the combination with a clip comprising
angularly arranged face portions and
bolt means connecting said portions, of spoke

stays formed with enlarged headed extremi-
ties for anchorage to said face portions and
a stay formed with an enlarged looped ex- 10
tremity for connection to said bolt.

In testimony whereof I affix my signature.

JOHN P. TARBOX.
